(57) CLAIM

The ornamental design for a front face of a vehicle wheel, as shown and described.

DESCRIPTION

FIG. 1 is a front view of a front face of a vehicle wheel showing my new design;

FIG. 2 is a front and left side perspective view of the front face of a vehicle wheel shown in FIG. 1;

FIG. 3 is a different side and front perspective view of the front face of a vehicle wheel shown in FIG. 1;

FIG. 4 is a front view of a front face of a vehicle wheel showing a second embodiment of my new design;

FIG. 5 is a front and side perspective view of the front face of a vehicle wheel shown in FIG. 4; and,

FIG. 6 is a different front and side perspective view of the front face of a vehicle wheel shown in FIG. 4.

Where included, broken lines showing environment or structure are for illustrative purposes only and form no part of the claimed design.
